US00D968077S

(12) **United States Design Patent** (10) **Patent No.:** **US D968,077 S**
(45) **Date of Patent:** **** Nov. 1, 2022**

(54) **MOBILE PHONE STAND**

(71) Applicant: **DONGGUAN RUNBONE TECHNOLOGY CO., LTD**, Dongguan (CN)

(72) Inventor: **Zhi Pan**, Shenzhen (CN)

(73) Assignee: **DONGGUAN RUNBONE TECHNOLOGY CO., LTD**, Dongguan (CN)

(**) Term: **15 Years**

(21) Appl. No.: **29/794,004**

(22) Filed: **Jun. 9, 2021**

(30) **Foreign Application Priority Data**

Apr. 30, 2021 (EM) 008524656-0003

(51) **LOC (13) Cl.** **03-01**

(52) **U.S. Cl.** ..... **USPC** **D3/218**

(58) **Field of Classification Search**

USPC D14/251-253, 447, 440; D3/218, 215, D3/226, 224, 229

CPC A45F 2005/008; A45F 5/00; A45F 2200/0516; H04M 1/04

(57) **CLAIM**

The ornamental design for a mobile phone stand, as shown and described.

DESCRIPTION

FIG. 1 is a perspective view of a mobile phone stand showing my new design, shown in a first configuration of use;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the mobile phone stand shown in a second configuration of use;

FIG. 10 is a perspective view of the mobile phone stand shown in the first configuration of use and connected with a first phone holder;

FIG. 11 is a perspective view of the mobile phone stand shown in the first configuration of use and connected with a second phone holder; and,

FIG. 12 is a perspective view of the mobile phone stand shown in the first configuration of use and separated from the first phone holder.

The broken lines in the drawings depict portions of the mobile phone stand that form no part of the claimed design.

1 Claim, 12 Drawing Sheets
